UNITED STATES PATENT OFFICE.

ALTON B. CARTY AND ROY F. CARTY, OF WASHINGTON, DISTRICT OF COLUMBIA.

PUZZLE.

No. 925,752.

Specification of Letters Patent.

Patented June 22, 1909.

Application filed September 9, 1908. Serial No. 452,292.

To all whom it may concern:

Be it known that we, ALTON B. CARTY and ROY F. CARTY, citizens of the United States, residing at Washington, in the District of Columbia, have invented new and useful Improvements in Puzzles, of which the following is a specification.

Our invention pertains to puzzles; and it contemplates the provision of a puzzle which 10 while susceptible of being cheaply produced requires considerable study and skill in its solution, and is therefore calculated to afford considerable diversion and entertainment to adults as well as to children.

With the foregoing in mind the nature of the invention and its novelty and utility will be fully understood from the following description and claims when the same are 15 read in connection with the drawings, accompanying and forming part of this specification, in which:

Figure 1 is a general view of the puzzle constituting the best practical embodiment of our invention of which we are cognizant, 20 as the same appears when ready to be worked out or solved. Fig. 2 is a view similar to Fig. 1 but showing the puzzle as solved and the movable member ready to be placed in the holding means, preferably an aperture, 25 provided for its reception. Fig. 3 is an enlarged detail view illustrating the body of the puzzle in edge elevation and also illustrating in an open state the several loops of the cord comprised in the puzzle. Figs. 4 and 5 are detail views illustrative of manipulations of the cord and movable member 30 resorted to in working the puzzle.

Similar letters designate corresponding parts in all of the views of the drawings, 35 referring to which:

A is the body of our novel puzzle, which for the sake of cheapness is preferably in the form of a card of pasteboard or other suitable material. The said body is provided at 40 *a* with a socket or holding means, preferably in the form of an aperture, and at two other points, preferably near the corners of the body remote from the socket *a*, the body is provided with comparatively small apertures *b* and *c* the walls of which are preferably protected by eyelets *d* as shown.

In addition to the body A our novel puzzle comprises a movable member B, and an endless cord C. The movable member B is 45 preferably of the same configuration as and of a size to snugly occupy the holding means

a of the body A, and its aperture is preferably protected by an eyelet *f*. The endless cord C is carried through the holding means *a* and the apertures *b* and *c* of the body A, and through the aperture *f* of the movable member B, and is looped after the manner best shown in Fig. 3.

Normally the movable member B is arranged as shown in Fig. 1, relative to the body A and the cord C, and the solution to be gained is the placing of the member B in the holding means *a* by manipulation of the said member B and the cord C relative to the body A. In this connection it is well to state that we contemplate providing the holding means *a* in a picture provided on the face of the body A and representing the White House.

The puzzle is solved as follows: The first 75 step looking toward the solution of the puzzle consists in passing the movable member B through the loop No. 1 in Fig. 1, after which the said loop No. 1 is drawn downwardly through the aperture *c* in the body 80 A. In this way two loops numbered 2 and 3 are provided below the body A as shown in Fig. 4, and the disk is then passed through the loops 2 and 3 in the order named. Then the cord or rather the loop 4 thereof, Fig. 5, 85 is drawn back through the aperture *c*, and then the movable member B being at the upper side of the body A is passed through the said loop 4 and is moved on the stretch of cord between the loop 4 and the holding 90 means *a* and is disposed in the latter, thus solving the puzzle.

It will be obvious from the foregoing that any desired picture may be employed 95 in lieu of the White House, or the picture may be altogether omitted without involving departure from the scope of our invention as defined in the claims appended; also, that either one movable member may be employed on the cord C or two or more movable members in the discretion of the manufacturer of the puzzle.

Because of its simplicity, inexpensiveness and amusement-affording qualities our novel puzzle constitutes a valuable advertising 105 medium and may be used to advantage as such even when given away in large numbers.

Having described our invention, what we claim and desire to secure by Letters Patent, is:

1. A puzzle comprising a movable mem-

22
ber, a body having holding means in the form of an aperture to fit the member and also having other apertures, and an endless cord on which said member is movable, extending through the holding means and the apertures of the body.

2. A puzzle comprising a movable member, a body having holding means in the form of an aperture to fit the member and also having other apertures, and an endless cord on which said member is movable, extending through the holding means and one

aperture of the body and having a loop extending through the remaining aperture of the body, said loop receiving portions of the cord at one side of the body.

In testimony whereof we have hereunto set our hands in presence of two subscribing witnesses.

ALTON B. CARTY.
ROY F. CARTY.
